UNITED STATES PATENT OFFICE.

EDWARD DANNER, OF TOLEDO, OHIO.

METHOD AND APPARATUS FOR FORMING GLASSWARE.

Application filed August 23, 1926. Serial No. 405,322.

This invention relates to the manufacture of glassware, and is directed to improvements and additions to the method and apparatus disclosed in my Patent No. 1,555,358, issued September 21, 1925, and includes some of the species disclosed in said patent. In another co-pending application, Serial No. 2,430,400, filed June 24, 1924, there are claims to another species and some broad claims covering both the species specifically claimed in that application and also the species claimed in this application, and, therefore, failure to make such broad claims in this application is not to be construed as an abandonment of the invention covered thereby.

The drawing or forming of glass in sheet form from a soft, tough, furnace tip or other directing means over which it flows, often causes a tendency for the sheet to acquire wrinkles and folds on the under side thereof having resultant with the directing means, especially if the glass is not at the proper temperature, while the opposite side of the sheet has a smooth, perfect fire finish.

An object of my invention is to overcome the above objection by the provision of a tip member or portion of an adjacent to the tip member a portion of the directing means which causes a separation of the flowing glass stream into two spaced laterally from the tip member and spaced at their outer sides to receive the burning heat and then causing a merging or uniting of the separate filaments into a single sheet with the fire finished surfaces of the sheet forming the outer surfaces of the sheet. With this method of forming the glass in sheet form, the temperature within the chamber in which the slab or other directing means is disposed may be varied to a considerable extent without giving the sheet a streaky appearance.

Another object of the invention is the provision of means of a simple and efficient character for changing the course of flow or merging of a sheet of glass while in a soft pliant condition without marring the surface thereof which comes in contact with the directing means.

Other objects and advantages of the invention will be apparent from the following detailed description thereof.

My invention in its broader aspect is susceptible of embodiment in numerous forms as to the nature of embodiment and a slight

modification of a part thereof are illustrated in the accompanying drawings, in which,—

Figure 1 is a central vertical longitudinal section of an apparatus embodying the invention with parts broken away. Fig. 2 is an enlarged fragmentary detail of the tip portion of the slab from which the glass flows in sheet form, together with the associated parts. Fig. 3 is a slightly modified form thereof with the tip arranged in a slightly different relation to the slab. Fig. 4 is a fragmentary side view of the casing showing an adjustable end bearing for the slab tip. Fig. 5 is a fragmentary, vertical section of the casing and of the slab tip adjusting means. Fig. 6 is a fragmentary side view of the casing similar to Fig. 4 showing a form of adjustment for the tip in Fig. 3. Fig. 7 is a vertical cross section on the line 7-7 in Fig. 1, together with the adjusting means for the sectional control gate, and Fig. 8 is a side elevation of such means.

Referring to the drawings, 1 designates a chamber containing molten glass and may be the refining chamber of a glass melting furnace. The glass flows from this chamber through a chamber 2 and into a chamber 3 which latter may be termed the tempering or drawing chamber for the flowing sheet. The bottom of the chamber 2, which chamber also serves as a tempering or refining chamber for the glass to assist in bringing it to proper condition for sheet forming, is formed by a trough 4. The flow of the glass over this trough is regulated, in the present instance, by a pair of gates 5 and 6, the former being adjacent to the inlet end of the chamber 2 and serving both as a gate for entirely cutting off the flow of glass from the chamber 1 when desired and also as a gate for regulating the thickness or depth of the stream flowing through the chamber 2. The gate 6 is composed of a plurality of sections 6' disposed one by side crosswise of the trough and independently adjustable to permit a varying of the thickness of the glass stream crosswise thereof as sheet forming conditions may require and for the purposes hereinafter more particularly described. The gates 5 and 6 also serve to separate the different chambers 1, 2 and 3 so that different temperature conditions may be maintained therein, each chamber having provision for independently heating or regulating the temperature therein, as well understood in the art. In chamber 2 burner receiving

openings in the side walls thereof are designated 21.

The stream of glass as it discharges from the end of the trough 4 into the chamber 3 5 flows onto and down the front or upper side of a sheet forming slab 7, which is preferably only inclined to a small extent from a vertical, as shown in Fig. 1. The slab 7 is stationarily mounted, bearing at its upper end rearwardly against the rear wall 9 of the chamber 3 immediately below the discharge end of the trough 4 and having its lower end supported at its rear edge by a base block 10 disposed within the lower portion of the chamber 3. The slab 7 and base block 10 cooperate with the wall 9 to form a chamber or compartment 22, which may connect with the chamber 3 if desired around the side edges of the slab 7, as shown in Fig. 5, or be entirely closed to said chamber.

The slab 7 is of trough form having edge strips or flanges 11 on its front side for limiting the width of a stream of glass flowing down the same. A tip 12 is mounted at the lower end of the slab for adjustment toward and away from the same to vary the spacing therebetween so that the glass stream flowing down the slab may be divided by the tip and portions flow around and down back the front and rear sides thereof, as illustrated, the two portions or films merging at the lower edge of the tip and flowing therefrom in a single stream. The tip 12 may also have rotary adjustment relative to the slab so that its position may be adjusted to suit the direction of movement or drawing of the sheet therefrom. It is found preferable in practice to flow the stream vertically by gravity from the tip and not to exert any stretching or drawing pull thereon, and the movement of the sheet may then be continued vertically until set and subsequently severed into sections, or it may be deduced while still in a soft or pliant condition from a vertical to a horizontal or other desired direction of travel, as illustrated in the drawings, so that the sheet may be directed in a horizontal direction through a tier, after which it may be severed into sections of desired length.

The tip 12 is preferably more or less rounded at its top and then tapers to a thin edge at its bottom or discharge portion to facilitate a joining of the glass films into a single sheet as they flow from the tip. The tip may be disposed in various relative to the lower end of the slab, being illustrated in Figs. 1 and 2 as partly disposed under the lower edge of the slab, and in Fig. 3, in which it is designated 12^a, as to advance of the lower end of the slab. The relative positions of the slab and tip are immaterial, however, provided the tip bears the proper

relation to the slab to effect a dividing into separate films of the sheet or stream of glass as it flows down the slab, and to then cause a merging of the films into a single sheet flowing from the tip. 70

The tip 12 is provided with end trunnions 13 projecting outwardly from the tempering chamber 3 through openings 14 in its respective sides, and each trunnion is journaled at its outer end in a bearing block 15 that is mounted for inclined adjustment in a guide bracket 16 fixed to the side frame 17. The bearing block 15 is attached to the lower end of an inclined adjusting screw 18, which may carry an adjusting nut 19 in engagement with the upper end of the bracket 16. The adjustment of the tip with the bearing blocks 15 effects a varying of the space between the tip and lower end of the slab so that more or less glass may flow 80 down the rear side of the tip as may be desired. The tip may be set in any desired position of rotary adjustment by turning the trunnions in the blocks 15 and then securing them in adjusted position by set-screws 20. The wall openings 14 may be closed around the trunnions 13 by fire brick 21, the arrangement of which may be changed to suit the adjustment of the trunnions. 95

The adjustment of the tip 12^a is substantially the same as that described for the tip 12 except that the adjustment is horizontal. In this case the trunnions 13^a are each journaled in a block 15^a, which is suspended by a screw 22 from a horizontally adjustable bracket member 23 and the horizontal position of the block is adjusted by side screws 24, which project in opposite directions from the block and are threaded through frame parts 25, as shown in Fig. 6. 100

While the tip may be made of any material suitable for the purpose it is preferably made of nichrome and may have fingers 26 projecting from the ends thereof in the direction of flow of a sheet therefrom to assist in maintaining the width of the sheet as it flows from the tip, as shown in Fig. 5. Each finger 26 is carried at the inner end of a stem 27 which projects lengthwise of the adjacent trunnion 13 and is adjustably carried by a clamp 28 projecting from the trunnions. 110

The chamber 3 in its lower portion is provided with an outlet opening 29 in line with the tip 12 and through which the sheet passes as it flows from the tip. Flames are directed against the front and rear faces of the sheet at or adjacent to its point of flow from the tip 12 from burners 30 and 31, which flames also act to maintain the proper heat within the chamber 3 so as to properly temper and maintain or impart the proper sheet forming consistency to the glass flowing down and from the slab and tip. 125 130

The deflecting means preferably employed for deflecting the sheet from a vertical to a horizontal, or substantially so, as it flows down and from the tip 12 comprises a curved member 32 of metal or other suitable material disposed so the tip 12 is positioned in the sheet while still in a soft or pliant condition, to bend down onto the concave side of the deflecting member whereby the course of the sheet is changed in conformance to the curve of the member, as illustrated in Fig. 1. In order to prevent the marring of the sheet or, if in a soft condition, the sticking of the same to the member 32 as it flows along the same in contact therewith, the surface of the member with which the sheet comes in contact with a composition 33 of graphite and carbon, such as is commonly used in candles for ladies and candles, or any other material of a nature to prevent marring, or sticking of hot, soft glass thereto may be employed. It is found, however, that very good results are obtained by the use of a graphite and carbon composition. The member 33 is preferably hollow and adapted to have a coating and circulated therethrough to prevent too high heating of the member, particularly the hot glass coming in contact therewith, as it is found that sticking of the sheet will occur a considerable portion of the time when the sheet passes between the deflecting member and passes between the deflecting member and the trough 4, as is also suitable for the purpose, the member 33 which is no longer required, the adjustment of the speed of flow of the sheet, the rate of flow, the feeding or deflecting member may have side engaging members disposed at intervals throughout the travel of the sheet as is common in sheet forming apparatus, as well understood in the art.

In the forming of sheet glass it is found desirable to vary the density or flow of the glass down the slab trough and the suitable means to effect such a varying flowing conditions are in many cases in the sheet glass itself or from separate, it is the usual practice to provide a projection at the edges of the sheet which at the corner, or end thereof, is made thicker. It is also found desirable to provide the glass sheet from the slab with a thickened edge portion, as is common for the sheet flow of the glass products. On the outer portion of the stream, but in the transition region at the edges of the sheet of sheet glass is accomplished by the process of forming, by separating the slab into a series of separate sections of unequal width by slots transversely of the trough, and independently adjustable so as to form a central member to the trough, as is shown in Fig. 7. The adjusting or passing means of placing a cable or other suitable flexible

member 36 extending upward from the respective slab over the guide sheave 37, thence transversely of the furnace over a respective guide sheave 38, and thence down to a single connecting member 39 having a threaded rod 40 projecting downward therefrom through an anchored hand-wheel nut 41 adjustable to effect a raising or lowering of the gate sections in unison. Each cable 36 is provided with a turn buckle 42, or other suitable means, for adjusting the length thereof to facilitate a relative adjustment of the gate sections with respect to the trough 4, as is apparent.

In the practicing of my invention, a molten stream of glass is permitted to flow in continuous regulated sheet form from the trough 4 down the slab 7 within the tempering chamber 2, the stream being divided at or adjacent to the lower end of the slab 7 into laterally separated films which flow around opposite sides of the tip 12 and then merge and flow together in single sheet form from the lower edge of the tip. The glass is in such a fluid condition as it flows down the tip 12 that any streaks caused on the rear or inner side of the sheet by reason of its contact with and flowing from the slab 7 will be eliminated before the glass leaves the tip 12, such elimination being assisted by the fire finishing action of the flame from the burner 31, that imparting a smooth fire finished coating to both sides of the sheet flowing from the tip, the tip contacting surfaces of the films which pass around opposite sides of the tip being brought together in vicinity of the sheet. The sheet as it leaves the tip flows downwardly by gravity into contact with the subjacent curved surface of the deflecting member 32 by which its course is changed, in the present instance, to a horizontal, such deflecting of the sheet taking place while the sheet is in a soft pliant or semi-soft condition to permit an easy flexing of the same as it follows the curved course of the deflecting member. The sheet thence passes into and through a lehr, being fed by any suitable feeding means through the lehr at the speed of flow of the same from the tip. The sheet as it leaves from the tip is contacted or narrowed somewhat in width from the width of the stream flowing down the slab. It is found, however, that in the production of some kinds of ware the best results are obtained by permitting such narrowing of the sheet rather than to provide width maintaining means therefore, as the edges of the sheet are formed perfectly smooth and straight thereby preventing the possibility of scarring the edge portions from the sheet as is necessary if width maintaining means is employed, and also obviating the necessity of grinding the sharp edges of the sheet off by severing the edge portions thereof, in other words, the sheet

may be formed the width desired for commercial use and provided in the formation thereof with perfectly straight free finished edges. For instance, if it is desired to obtain sheet glass for wind shield purposes, the sheet may be formed the desired width for the wind shield sections and used for such sections by merely severing the sheet in the desired lengths, no subsequent finishing of the edges being required. This is an important feature as it eliminates not only the large amount of work required in trimming sheets to desired size and grinding the sharp edges therefrom, but also eliminates the breakage and waste of glass which takes place in such operations. It is found in practice that the deflecting of the sheet while in its soft condition by the lubricated surface of the deflecting member 33 does not mar the surface of the sheet having contact with the deflecting member or lessen the brilliancy thereof.

By the terms "soft," "unset," "semiset" or "pliant" as used herein in describing the condition of the glass in the formed sheet when coming in contact with the deflecting means 33, is meant such a condition of the glass as will permit it to maintain its sheet shape and not be marred by contact with deflecting surfaces and at the same time will permit a free flexing thereof without breaking. The surface skins of the sheet, after leaving the tip or forming means 12 and before coming in contact with the deflecting means 33, become sufficiently chilled and set as to permit handling thereof without marring, the sheet, however, as a whole remains sufficiently soft or pliable to enable it to be freely bent or flexed without breaking. In view of this it is evident that the spacing between the forming means 12 and deflecting means 33 should be such that the surfaces of the sheet will have become sufficiently set before coming in contact with the deflecting means as to prevent marring of the contacting sheet surface by the deflecting means and that such space is dependent on the speed of flow, thickness and temperature of the glass and the rapidity of cooling of the sheet after leaving the forming means. In the appended claims the term "tip" refers to a terminal member small in comparison with the size of the main slab or directing member.

I wish it understood that my invention may be practiced by other apparatus than that illustrated and that the arrangement and form of the parts of the apparatus may be changed without departing from the spirit of the claims.

Having thus described my invention, what I claim as new, and desire to secure by Letters Patent, is:

1. The method of forming sheet glass, consisting in causing molten glass to flow

along a directing means and around opposite sides of a tip portion disposed at the discharge end of the means, the glass merging at the outer edge of the tip portion and flowing therefrom in single sheet form. 70

2. The method of forming sheet glass, consisting in flowing a stream of molten glass along and from a directing member, thence around opposite sides of a tip member and causing the stream to merge and 75 flow from the tip member in single sheet form, the directing member and tip member being disposed in a heated atmosphere.

3. The method of forming sheet glass, consisting in flowing a stream of molten 80 glass along and from a directing means, thence around a tip member, the stream merging and flowing vertically in single sheet form from the tip member, and providing a heated atmosphere in which the 85 directing means and tip member are disposed.

4. The method of forming sheet glass, consisting in flowing a stream of molten glass along and from a directing member 90 and in divided film form around opposite sides of a tip member, the films merging and flowing in single finished sheet form from the tip member, and regulating the stream to cause a predetermined variance of the 95 depth thereof crosswise of the sheet.

5. The method of forming sheet glass, consisting in flowing a stream of molten glass along and from a directing means and in divided film form around opposite sides 100 of a tip member therefor, the films merging and flowing by gravity in single finished sheet form vertically from the tip member, and regulating the stream to cause a predetermined variance of the depth thereof 105 crosswise of the sheet.

6. The method of forming sheet glass, consisting in flowing a stream of molten glass along and from an inclined directing surface, thence around opposite sides of a 110 tip member and causing the stream to merge and flow vertically downward from the tip member in single sheet form, and deflecting the sheet while still in a soft pliant condition towards a horizontal direction. 115

7. The method of forming sheet glass, consisting in flowing a stream of molten glass along and from a directing surface onto a curved intercepting surface, thence in first diverging, and then converging directions along and from directing surfaces. 120

8. The method of forming sheet glass, consisting in flowing molten glass by gravity down an inclined member in a heated atmosphere, the glass flowing around opposite 125 sides of a dividing means at the discharge end of the member and thence merging and flowing therefrom in single sheet form.

9. The method of forming sheet glass, consisting in flowing a regulated stream of 130

- molten glass along and down a directing and width regulating means, causing a splitting of the stream laterally of its face by said means at the discharge end thereof to form separated films, having their inner faces only in flowing contact with the directing means, subjecting the separated films to a heated atmosphere to temper the same and to heat finish the outer surfaces thereof, and merging the films and flowing them in single sheet form from the directing means.
10. The method of forming sheet glass, consisting in flowing molten glass from a source of supply down an inclined slab through a heated atmosphere and from the slab around opposite sides of a separating means and then uniting the separated portions of the glass and flowing them from the means in single sheet form.
15. 11. The method of forming sheet glass, consisting in flowing a stream of molten glass from a source of supply down a slab through a heated atmosphere, separating the stream into laterally spaced films at the discharge end of the slab and then uniting the films and flowing the same in single sheet form, and regulating the stream flowing down the slab to impart a predetermined varying depth thereto crosswise of the slab.
20. 12. The method of forming sheet glass, consisting in flowing a stream of molten glass from a source of supply through a tempering chamber down an inclined slab, splitting the stream at the discharge end of the slab into laterally separated films having their inner faces only in flowing contact with the splitting means and then merging the films and flowing them in single sheet form from the tempering chamber.
25. 40. regulating the stream to vary its thickness throughout its width as it flows onto the slab and causing a curved deflection of the sheet flowing from the slab by contact of the sheet with a subjacent curved deflecting means.
30. 13. In an apparatus for forming sheet glass, a heated chamber, means for directing the flow of molten glass through the chamber and from the discharge end of which means the glass flows in sheet form, said means having a tip at its discharge end around which the glass flows in separate films and from which it passes in single sheet form.
35. 14. In an apparatus of the class described, a heated chamber, a downwardly extending means for directing the flow of molten glass through the chamber, and means at the discharge end of the inclined member for laterally separating the glass into films with their outer sides exposed to the heat of the chamber, the films merging and flowing in single sheet form from the discharge end of the means.
40. 15. In an apparatus for forming sheet glass, means for directing the flow of a stream of molten glass and having an inclined portion from the discharge end of which the glass flows in sheet form, and means having provision at its discharge end for a portion of the glass stream to flow in film form to and along the rear side thereof and to merge with and form one side of the sheet flowing from the means, and means for maintaining the stream of glass at proper temperature and for heat finishing the outer surfaces of the stream and film.
45. 16. In an apparatus of the class described, means for directing the flow of a stream of glass from a source of supply and including a slab inclined from a vertical direction, the upper side of which the glass flows in sheet form, said slab having provision at its discharge end for a portion of the stream to flow in film form to and along the rear side thereof and to merge with the sheet as it flows from the slab, and means for maintaining the glass at proper temperature so it flows over the means and down and from the slab.
50. 17. In an apparatus for forming sheet glass, a heated chamber, a downwardly directed slab disposed therein, means for directing the flow of molten glass to and down the inclined face of the slab, said slab having a tip portion adapted to divide the stream into separated films which merge and flow therefrom in sheet form, the outer surfaces of the film being exposed to the heat of the chamber.
55. 18. In an apparatus for forming sheet glass, means for directing the flow of a stream of glass from a source of supply and including an inclined portion down which the glass flows by gravity, a discharge tip for the inclined portion which divides the stream into films that merge in single sheet form at the discharge end thereof, and means for maintaining the stream of glass at proper temperature and for heat finishing the outer surfaces of the stream and film.
60. 19. In an apparatus for forming sheet glass, means for directing the flow of a stream of glass from a source of supply including a downwardly directed heated slab having an adjustable tip member at its discharge end which divides the stream into laterally separated films that merge and flow in single sheet form from the discharge end thereof, and means for maintaining the stream of glass at proper temperature and for heat finishing the outer surfaces thereof.
65. 20. In an apparatus for forming sheet glass, a heated chamber, a downwardly directed slab disposed within the chamber for directing the flow of molten glass thereto, a tip for the slab around opposite sides of which the glass flows, and from which it discharges in single sheet form, the tip being

adjustable to vary the thickness of the films and to suit the direction of desired flow of the sheet therefrom.

21. In an apparatus of the class described, a slab disposed in a heated atmosphere and along which molten glass is permitted to flow in regulated stream form, and a tip member for the discharge end of the slab which laterally separates the stream into films and then permits them to merge and flow therefrom in single sheet form, the tip member being adjustable relative to the slab to vary the thickness of the films flowing around the same.
- 15 22. In an apparatus for forming sheet glass, a heated chamber having an opening in its bottom portion, a downwardly directed slab disposed within the said chamber and down which molten glass is permitted to flow by gravity in regulated stream form, and thence in the form of a sheet through said opening, the slab having provision at its discharge end for dividing the stream laterally into films which merge and form the sheet and which are exposed at their outer sides to the chamber heat.
- 20 23. In an apparatus for forming sheet glass, means for directing the flow of a stream of glass from a source of supply and including a slab, said slab having provision at its discharge end for causing a dividing of the stream into separate films which merge and flow in single sheet form from the slab, means for maintaining the glass at proper temperature as it flows over the means and along the slab, and width maintaining members projecting from the discharge end of the slab in the direction of the flow of the sheet therefrom and in engagement with the respective edge portions of the sheet.
- 25 24. In an apparatus of the class described, a slab along and from which molten glass may flow in sheet form, and members projecting from the discharge end of the slab in the direction of movement of the sheet therefrom and in engagement with the edges thereof to maintain the width of the sheet after leaving the slab.
- 30 25. In an apparatus of the class described, a slab along and from which molten glass may flow in sheet form, and members projecting from the discharge end of the slab in the direction of movement of the sheet therefrom and in engagement with the edges thereof to maintain the width of the sheet after leaving the slab, said members being adjustable transversely of the slab.
- 35 26. In an apparatus for forming sheet glass, a slab down and from which molten glass flows in sheet form, said slab having extensions at the edges of its discharge end which project in the direction of flow of a sheet therefrom.
- 40 27. In an apparatus for forming sheet

glass, a slab down and from which molten glass flows in regulated sheet form and having fingers projecting from its discharge end adjacent to its opposite edges and in the direction of flow of a sheet therefrom to serve as width maintaining means for a sheet.

28. In an apparatus of the class described, means for directing the flow of a stream of molten glass from a source of supply and including a downwardly directed slab from which the glass flows in sheet form, means for maintaining the glass at proper temperature as it flows along and from the means, fingers projecting from the discharge end of said means in the direction of flow of the glass therefrom and engaging the edges of a sheet to maintain the width of the sheet a predetermined distance as it flows from the directing means, said fingers being adjustable crosswise of a sheet.

29. In an apparatus for forming sheet glass, means having a directing surface along which molten glass may flow in sheet form, limiting means spaced from said surface and adapted to determine the thickness of glass flowing along said surface, and independent means for varying the distance of different portions of said limiting means from said directing surface.

30. In an apparatus for forming sheet glass, means for directing the flow of molten glass and from which it passes in sheet form, and a gate cooperating with said means to regulate the flow of glass thereover, said gate comprising a plurality of sections independently adjustable to vary the thickness of the stream at different points throughout its width.

31. In an apparatus of the class described, means for directing the flow of molten glass and from which it passes in sheet form, and a gate cooperating with the means to regulate the flow of glass thereover, said gate comprising a plurality of sections placed side by side and capable of relative vertical adjustment, and means operable to impart simultaneous or relative adjustment to the gate sections.

32. In an apparatus for forming sheet glass, means for directing the flow of a stream of molten glass and from which the glass flows by gravity in sheet form, means for applying heat to the glass in its flow along said means, and a deflecting member subjacent to the discharge end of said means disposed to contact with and laterally deflect the course of movement of the flowing sheet while the sheet is still in a pliant condition, said deflecting member having its sheet contacting surface composed of a smooth insulating material.

33. In an apparatus for forming sheet glass, means for directing the flow of a stream of molten glass and from which the glass flows by gravity in sheet form, means

- for applying heat to the glass in its flow along said means, and a curved deflecting member subjacent to the discharge end of said means disposed to coat with and laterally deflect the course of movement of the flowing sheet while the sheet is still in a pliant condition, said deflecting member having its sheet coating surface composed of a composition containing graphite.
34. In an apparatus for forming sheet glass, means for directing the flow of a stream of molten glass and from which the glass flows by gravity in sheet form, means for applying heat to the glass in its flow along said means, and a curved deflecting member subjacent to the discharge end of said means disposed to coat with and laterally deflect the course of movement of the flowing sheet while the sheet is still in a pliant condition, said deflecting member having its sheet coating surface composed of a graphite and carbon compound.
35. In an apparatus for forming sheet glass, means for directing the flow of a stream of molten glass and from which the glass flows by gravity in sheet form, means for applying heat to the glass in its flow along said means, and a curved deflecting member subjacent to the discharge end of said means disposed to coat with and laterally deflect the course of movement of the flowing sheet while the sheet is still in a pliant condition, said deflecting member being hollow to permit the circulation of a cooling fluid therethrough, and having its sheet coating surface composed of a graphitic composition.
36. In an apparatus for forming glass-
- ware, means to supply a stream of molten glass and directing means stationary during operation presenting a curved upper surface in position to intercept the stream and presenting downwardly converging side surfaces over which films of glass may flow from said upper surface.
37. In an apparatus for forming sheet glass by flowing the molten glass from a receptacle over an overflow lip, a flow regulator for the molten glass comprising a gate or barrier lowered into the surface glass and projecting further into the glass at the center of the receptacle than adjacent the edges thereof.
38. In an apparatus for forming sheet glass by flowing the molten glass from a receptacle over an overflow lip, a flow regulator for the molten glass, comprising a practically continuous gate or barrier formed of a series of units arranged edge to edge transversely of the receptacle and capable of being lowered into the stream of molten glass to varying depths.
39. In an apparatus for forming sheet glass by flowing the molten glass from a receptacle over an overflow lip, a flow regulator for the molten glass, comprising a practically continuous gate or barrier formed of a series of units arranged edge to edge transversely of the receptacle, and an adjusting screw for each unit whereby the units may be individually lowered into the flowing glass to different depths.

In testimony whereof I have hereunto subscribed my name to this specification.

EDWARD DANNER.
